UNITED STATES PATENT OFFICE

ERNEST J. DUBOIS, OF LOWELL, MASSACHUSETTS

COPYHOLDER

Application filed March 6, 1931. Serial No. 520,657.

This invention relates to a device which is designed and adapted for readably handling printed matter, and has especial reference to a device or holder which may be used advantageously for handling copy in connection with the operation of a linotype machine.

An object of the invention is to provide a simple, strong, durable and efficient device of the indicated character which may be easily attached to any standard type of linotype machine or other analogous machine, for the purpose of enabling a person manipulating a keyboard or setting up type to copy long lists of names and addresses, stock market quotations, law work, railroad time tables, price lists, etc., from sheets provided for that purpose, with a little effort and with slight liability of error.

Another object of the invention is the provision of means in a device of the indicated character whereby the sheet of copy, after once being attached to the device, requires practically no adjustment and whereby the entire device requires but a simple manipulation to bring the desired information or printed matter within the line of vision of the user.

Another object of the invention is the provision of improved means in a device of the indicated character, whereby, as a line of copy is set up in type, the copy, as the result of a simple movement on the part of the user, may be advanced to present the next line of the copy.

A further object of the invention is the provision of simple and improved means in a device of the indicated character whereby the free end of a copy sheet, in case it is a long sheet, may be kept out of the line of vision of the user, so that only that portion of the copy which is being copied will be exposed to view.

Other objects of the device of the present invention are in part as follows: The copy to be set up in type is brought near to the vision of the operator; only one hand is required to move the copy; jumping or omitting of lines to be set in type will not be likely to occur; the handling and folding of long copy sheets and adjusting of the reading bar at each line

will be eliminated; the copy sheet will be kept clean; proof or other corrections are made with ease in a minimum of time; there will be no shade from light rests on the reading gauge since the latter will be below the particular line of copy being read, thereby providing good vision of the copy at all times; the distance between the copy being set and the type falling in assembly is nearer and almost on the same elevation making it easier for the operator to gaze from one to the other and decreasing mistake advantageously; and the operator will increase his production with less effort on his part.

With the foregoing, other objects of the invention will appear from the embodiment of the invention which by way of example is described in the following specification and illustrated in the accompanying drawing, in which—

Figure 1 is a front view of a device embodying the features of the invention;

Figure 2 is a plan view;

Figure 3 is a section on the line 3—3 of Figure 1;

Figure 4 is a section on the line 4—4 of Figure 1;

Figure 5 is a fragmentary section taken on the line 5—5 of Figure 3.

Referring now more particularly to the drawing it will be apparent that there is shown a base 10 which is designed and adapted in one of the uses of the device to be readily placed on the frame of a linotype machine directly in front of the operator. Suitable bearing pedestals 11 are respectively secured as at 12 to the opposite ends of the base 10.

A shaft 13 is rotatably supported by the bearings of the pedestals 11. A roll or drum 14 of hollow construction is mounted on the shaft 13 to rotate therewith as a part thereof. The roll 14 is arranged between the pedestals 11. The shaft 13 has a manipulating knob or handle 15 on each end thereof for the purpose of rotating the roll 14.

Means is provided for clamping one end of a copy sheet on the roll 14 so that it may be progressively wound on the roll to present the reading matter thereon in the line of vi-

sion of the user as desired. The said means in the present instance includes a separate peripheral section 16 of the roll 14 having a radial, inwardly extending flange 17. The 5 section 16 is yieldably retained in position in relation to the major cylindrical or peripheral wall of the roll 14 by springs 18, each of which has one end thereof connected with the flange 17 as at 19 and its opposite end connected with the shaft 13 as at 20. It will be understood that the section 16 is movable into and out of a clamping position. In order to cause the movement of the clamping section 16 out of its clamping position, there 10 are provided L-shaped members or hooks 21 respectively on the opposite ends of the flange 17 which project through slots 22 respectively in the ends of the roll 14. A rod 23 extends through the roll 14 and its opposite ends project through the ends of the roll thereby supporting the rod for rotatory or 15 rocking movement. A finger piece or manipulator 24 is secured to each end of the rod 23 by a set screw or the like 25. Each manipulator 24 is engageable with the L-shaped member 21 related thereto. By pressing downwardly on either one of the manipulators 24, the clamping section 16 will be moved 20 out of its clamping position, as shown in dot 25 and dash lines in Figure 3. When pressure on the manipulator 24 is released the springs 18 return the clamping section 16 to its clamping position. It will be apparent that the members 21 in contact with the walls of 30 the slots 22 will guide the clamping section 16 in its movement into and out of the clamping position. On reference to Figure 4 it will be apparent that a copy sheet 26 has one end 35 27 thereof clamped on the roll 14, the said end being clamped or gripped by the section 16. The free end of the sheet 26 is received in a rolled condition by portions of a plurality of supporting members 28 secured as at 29 to the base 10 at the rear thereof. 40 In the case of an exceptionally long copy sheet the free end thereof may be supported in rolled condition in an orderly manner by the upper, open, loop shaped ends 30 of the members 28.

45 In order to co-operate with the cylindrical surface of the roll 14 to facilitate the winding of the copy sheet 26 thereon and to prevent the same from slipping or leaving the surface of the roll there are provided small 50 rollers 31 respectively at the front and back of the roll 14, each of said rollers 31 having rubber sections 32. The opposite ends of each roller 31 are respectively received in guides 55 33 secured to or formed integral with the pedestals 11. Each end of each roller 31 has connected therewith one end of a spring 34 whose opposite end is connected with a pin 35 carried by the related guide 33. In this manner the rollers 31 are yieldingly held in con-

tact with the copy sheet 26 for the purpose mentioned hereinabove.

In accordance with another feature of the invention there is provided a reading gauge 36 which is supported by the front roller 31. The gauge 36 will be disposed longitudinally of the roll 14 so that the copy or printed matter on the sheet 26 may be readily observed by the operator. If desired, the gauge 36 may have secured thereto spring fingers 37 which 70 keep it in yieldable contact with the sheet 26, the said fingers 37 also being engageable with the sheet 26.

In the operation of a linotype machine, it is one of the common duties of the operator to copy lists of names and addresses, or other data, especially for use in directories and telephone books, time tables, price lists, bank reports, etc., from long lists of such information furnished the operator on sheets of various sizes, lengths and widths. These sheets are printed in very small type and oftentimes have corrections noted thereon. It is a very difficult matter for an operator to set up type and copy this information, especially where the copy is not conveniently disposed, it being placed far from the vision of the operator, and requiring the folding of the sheet of copy many times, together with adjusting the copy under a reading gauge at each line to be set.

From the foregoing it will be apparent that the operator of a linotype machine may place a copy sheet on the device by first taking one end of the copy sheet having the beginning of the printed matter thereon in one hand and with the other hand he may press on one of the manipulators 24 to raise the clamping section 16. The end of the copy sheet may 100 then be inserted into the roll 14, whereupon the manipulator 24 may be released and as a consequence the section 16 under the influence of the springs 18 will cause the section 16 to clamp or grip the end of the sheet. The roll 14 may then be turned to bring the first line of the copy sheet to be set above the reading gauge 36. The free end of the copy sheet may be placed in the ends 30 in a rolled condition. The operator may then start setting lines and will rotate or turn the roll 14 as 105 may be desired. When all lines are set as may be desired from this particular copy sheet, the operator merely grabs the bottom end as it passes beyond the reading gauge 36 and pulls out the sheet which unwinds from the roll 14 without touching the latter.

It is to be understood that the invention is not restricted to the precise arrangement of parts shown and described, as details of construction may be modified and rearranged without departing from the spirit of the invention, the scope of which is limited only by the terms of the appended claims.

I claim:

1. A copy holder comprising a rotatable roll, means for clamping one end of a copy sheet on the roll, means at the rear of the roll to receive and support the free end of said sheet in rolled condition up out of the way and enabling the sheet to be wound on said roll to present the reading matter on said sheet in the line of vision of the user as desired, and guide rollers which resiliently co-operate with said roll to guide said sheet and also to keep it from slipping or leaving the surface of said roll.

2. A copy holder including a hollow rotatable roll, and means carried by the roll for clamping one end of a copy sheet on the roll so that the sheet may be wound thereon to present the reading matter on the sheet in the line of vision of the user as desired, said means comprising a clamping member which forms a peripheral section of the roll and which extends the entire length of the roll, projections on said clamping member extending outwardly through slots in the ends of the roll respectively, springs connected with the clamping member and roll to retain the clamping member in the clamping position, and pivoted manipulators on the roll which cooperate with said projections to move the clamping member to a released position.

3. A copy holder comprising a base, bearing pedestals arranged on the base in spaced relation to each other, a roll to receive a copy sheet, said roll having means supported by the bearings of said pedestals mounting the roll for rotation, guides on each of said pedestals arranged diametrically opposite each other in relation to the corresponding end of said roll, rollers each having its ends respectively disposed in a pair of said guides respectively on said pedestals, said rollers thus being mounted for movement toward and away from the peripheral surface of said roll, and tension means connected with said roller ends and said guides to resiliently retain said rollers in clamping engagement with a sheet arranged on said roll to keep the sheet from slipping or leaving the surface of the roll.

4. A copy holder comprising a base, bearing pedestals arranged on the base in spaced relation to each other, a roll to receive a copy sheet, said roll having means supported by the bearings of said pedestals mounting the roll for rotation, guides on each of said pedestals arranged diametrically opposite each other in relation to the corresponding end of said roll, rollers each having its ends respectively disposed in a pair of said guides respectively on said pedestals, said rollers thus being mounted for movement toward and away from the peripheral surface of said roll, tension means connected with said roller ends and said guides to resiliently retain said rollers in clamping engagement with a sheet arranged on said roll to keep the sheet from

slipping or leaving the surface of the roll, and a reading gauge carried by one of said rollers.

5. A copy holder comprising a base, bearing pedestals arranged on the base in spaced relation to each other, a roll to receive a copy sheet, said roll having means supported by the bearings of said pedestals mounting the roll for rotation, guides on each of said pedestals arranged diametrically opposite each other in relation to the corresponding end of said roll, rollers each having its ends respectively disposed in a pair of said guides respectively on said pedestals, said rollers thus being mounted for movement toward and away from the peripheral surface of said roll, tension means connected with said roller ends and said guides to resiliently retain said rollers in clamping engagement with a sheet arranged on said roll to keep the sheet from slipping or leaving the surface of the roll, a reading gauge carried by one of said rollers, and spring fingers respectively positioned on said gauge to bear on said sheet to aid in keeping the gauge in yieldable contact with the sheet.
